UNITED STATES PATENT OFFICE.

AUGUST F. LUZZI, OF HOUSTON, TEXAS, ASSIGNOR TO MILTON B. MCLEAN.

VIBRATOR.

Application filed May 12, 1925. Serial No. 29,674.

To all whom it may concern:

Be it known that I, AUGUST F. LUZZI, a citizen of the United States, residing at Houston, in the county of Harris and State 5 of Texas, have invented certain new and useful Improvements in a Vibrator, of which the following is a specification.

This invention relates to new and useful improvements in a vibrator.

10 One object of this invention is to provide an implement of the character described specially designed for attachment to a dental hand piece and provided for the purpose of massaging and exercising the gums and 15 other parts of the mouth, in the treatment of pyorrhea and other mouth diseases.

Another object of the invention is to provide a vibrator which may be operatively connected with the chuck of the conventional 20 dental drilling appliance, for operation.

With the above and other objects in view this invention has particular relation to certain novel features of construction, operation and arrangement of parts, an example of 25 which is given in this specification and illustrated in the accompanying drawings, wherein:—

Figure 1 shows a plan view of the vibrator.

30 Figure 2 shows a side view thereof, applied to a dental handpiece.

Figure 3 shows a sectional view thereof taken on the line 3—3 of Figure 2, and

35 Figure 4 shows a sectional view thereof, taken on the line 4—4 of Figure 2.

Referring now more particularly to the drawings, wherein like numerals of reference designate similar parts in each of the figures, the numeral 1 designates the conventional 40 dental hand piece, which contains the usual chuck (not shown) for receiving the dental drill.

The numeral 2 designates a U-shaped frame, preferably formed of rather stiff 45 wire. A clamp member 3 is provided, which is of a contour to fit around one side of the hand piece, and one end of which has flexible clamp jaws 4, 4 which clamp around said hand piece. The other end of this clamp 50 member is upturned, forming a thumb rest 5.

The closed end of the frame is upturned and works in a transverse bearing 6 in the clamp member 4. The arms of the frame are connected, and held comparatively rigid, 55 by an arcuate bridge 7, thus preventing the relative twisting of said arms, and holding

them in alignment while the vibrator is in use. Beyond this bridge the arms are bent toward each other or converge, and their free ends are parallel. The parallel portions are also connected by a bridge 8 having a central bearing 9.

The numeral 10 designates an oblong friction, or massaging member, preferably formed of rubber, or similar material, and which is fastened to the free ends of said arms of the frame. These arms are preferably inserted endwise into said friction member, but do not extend its full length, so as to permit its free end to yield, or bend, and thus more easily follow the contour of the mouth, in use and not to be too severe in application to the tender parts. One side of the member 10 has a plurality of projections or teeth 11, and on its other side, at 75 its free end, it is formed with a vacuum cup 12. The teeth are for friction, or massaging purposes, while the application of the vacuum cup promotes circulation.

A shaft 13 is provided. One end of this shaft is adapted to be inserted in the hand piece chuck by means of which the shaft is rotated, and the other end of the shaft is eccentric or offset and works in the bearing 9.

As the shaft is rotated it is obvious that a vibratory movement will be imparted to the member 10, and when applied to the parts to be treated will massage the same and induce a healthy circulation thereof, with beneficial results.

What I claim is:

1. A vibrator including a U-shaped frame, an anchor with which the frame is connected, a bridge connecting the arms of said frame, a bearing carried by the frame, a shaft having an eccentric wrist which works in said bearing, a massaging member formed of yieldable material into which the free ends of the frame arms are inserted so as to leave 100 a yieldable free portion at the outer end of said massaging member.

2. A vibrator including a U-shaped frame, an anchor with which the frame is connected, a bridge connecting the arms of said frame, a bearing carried by the frame, a shaft having an eccentric wrist which works in said bearing, a massaging member formed of yieldable material into which the free ends of the frame arms are inserted so as to leave 105 a yieldable portion at the outer end of said massaging member, a vacuum cup on one

side of said member and tooth like projections on the other side of said member.

3. A vibrator including a clamp formed with jaws, a U-shaped frame whose closed end has a bearing in said clamp, a pair of bridges connecting the arms of the frame, one of said bridges having a bearing, a shaft having an eccentric wrist which works in said bearing, a resilient massaging member

into which the free ends of the arms are inserted only part of the way leaving the outer end of said member yieldable, a vacuum cup on one side of said member and projecting teeth on the other side thereof.

In testimony whereof I have signed my name to this specification.

AUGUST F. LUZZI.
